UNITED STATES PATENT OFFICE.

JOSEPH STUART MITCHELL, OF CHICAGO, ILLINOIS, ASSIGNOR TO SULLIVAN MACHINERY COMPANY, A CORPORATION OF MASSACHUSETTS.

METHOD AND APPARATUS FOR DRILLING HOLES.

Application filed March 26, 1919. Serial No. 285,379.

To all whom it may concern:

Be it known that I, JOSEPH S. MITCHELL, a citizen of the United States, residing at Chicago, in the county of Cook and State 5 of Illinois, have invented certain new and useful Improvements in Methods and Apparatus for Drilling Holes, of which the following is a full, clear, and exact specification.

10 My invention relates to methods and apparatus for drilling holes.

One object of the present invention is to provide an improved hole deflecting means, and more especially a means for deflecting a 15 core drill so that a new core may be obtained hundreds of feet under ground without having to start a new hole. Another object is to provide an improved deflecting means which may be used at any point in a hole for 20 deflecting the hole in any direction desired. These and other objects and advantages of my invention will, however, hereinafter more fully appear.

In the accompanying drawings I have 25 shown one embodiment which my invention may assume in practice, although it is to be understood that the same is used for illustrative purposes only and that the invention is not limited to the embodiment herein 30 shown.

In these drawings,—

Fig. 1 is a longitudinal sectional view of a deflected hole with my improved deflecting means shown therein.

35 Fig. 2 is a sectional view of a hole with my deflector therein, part of the deflector being shown in section.

Fig. 3 is a side elevation, partly in section, of the lower part of the deflector.

40 Fig. 4 is a central longitudinal section through my improved core drill.

Fig. 5 is a transverse section taken on the line 5—5 of Fig. 2.

In the illustrative construction shown, I 45 preferably employ as a deflector a deflecting wedge 1, preferably made of a plurality of parts, herein two, the upper part 2 being secured to the lower part 3 by any suitable means, such as the overlapping and riveting 50 of the ends of the sections as shown at 4. For placing the wedge 1 in position, I preferably provide near the top of the section 2 a plurality of small holes 6 so that the wedge may be fastened by any suitable

means, such as rivets or bolts, to a drill rod 55 7. The inclined or longest face of the wedge is preferably concave, as shown at 5, in order that the wedge or deflecting member may more accurately guide a cutting tool. Near the top of the upper section 2 of the 60 wedge, I also provide a small inclined hole 8, for purposes to be more fully hereinafter described. I also provide near the bottom of the larger wedge section 3 an inclined hole 9 passing from the concaved face 5 65 through the wedge to the base thereof. As will be noted, this end of the wedge 3 is also adapted for attachment to a pipe or other supporting means through the provision of a threaded projection 10. 70

In the improved form of my device herein disclosed, I also provide a wedge supporting and anchorage means which preferably consists of two pipe sections 11 and 12 having elongated interlocking teeth 13 75 and 14, the upper section 11 being provided with a threaded end 15, whereby this section may be securely attached to the lower wedge section 3. The two pipe sections 11 and 12 may be secured together by any means desired, but for purposes which will more fully hereinafter appear I preferably unite these two pipe sections by means of a wooden core or plug 16. This plug has a driving fit in the upper section 11, but is 80 85 preferably secured to both sections by spikes 17 and 18.

In my improved drilling apparatus, which cooperates with the deflecting means above described for boring a deflected hole, 90 I preferably use a drill tube section 19 which carries on its lower end a drill bit 20 which may of itself comprise a cutting tool or it may carry cutting instruments, as, for instance, diamonds. This drill tube section 95 19 is further provided with a core retaining means (not shown) of a type common in core drills to facilitate the raising of a core to the surface. The drill tube section 19 may, if desired, be attached to another 100 drill tube section, as 21, or it may be attached directly to the drill rod. In the form of my invention shown in the drawings, the drilling apparatus is of the core drilling type, and I preferably use a second drill tube section 21 in order that the core obtained during each drilling operation may 105 be of great length. The drill sections are

preferably united by a swelled coupling 22 carrying on each side thereof threaded nipples 23 and 24 to facilitate the connecting of the coupling to the two pipe sections 19 and 21. This coupling 22 is preferably formed as a swelled coupling in order that the periphery of the coupling will extend outside the periphery of the drill tools to enable the operator to properly seat cutting instruments, such as diamonds, in this coupling and thus form a reaming instrument. The drilling apparatus just described is connected to the rather inflexible drill rod 7 by a smaller flexible hollow drill rod 25, this drill rod 25 being preferably connected with the drill tube 21 by two couplings 26 and 27.

In the operation of my improved apparatus for deflecting holes, when it is found necessary to change the direction of the hole, as may occur when a substance is encountered which cannot be easily drilled through or when in core drilling a poor core has been obtained and it is desired to obtain a new core for a part of the depth of the original hole 28, my improved deflector is inserted in the original hole substantially as shown in Fig. 2. To facilitate the insertion of the deflector, and to prevent the end of the drilling apparatus from engaging the upper and narrow end of the deflector, the original hole 28 is preferably reamed, as shown at 29, from a point about ten feet above the bottom of the hole to a point above the position which the upper end of the deflector would occupy when resting against the bottom of the hole. If desired, the deflector may be used without fastening it securely in a predetermined position in the hole, but I preferably pour into the hole a quantity of plaster of Paris, clay, or other suitable material, as shown at 12', and force the pipe section 12 into this material by applying hydraulic or other pressure to the drill rod 7. After the deflector has been properly positioned in the bottom of the original hole, as above described, additional pressure is applied to the rod 7 sufficient to shear the rivets or bolts which attach the rod to the deflector, and the rod is then withdrawn.

A drilling mechanism such as is shown in Fig. 4 may then be attached to the lower end of the drill rod 7 and the drilling operation may be carried on in the ordinary way. The reaming, swelled coupling 22 reams the deflected hole and prevents binding of the drilling mechanism in this new hole. If the angle of deflection is small or the material drilled quite soft, this reaming coupling need not necessarily be used. The small flexible rod 25 will bend easily without breaking and without binding in the hole, and greatly increases the efficiency of the drilling apparatus. If the depth of the de-

flected hole is very great, several sections similar to the small drill rod 25 may have to be added as the deflected hole is deepened.

The angle of deflection shown in Fig. 1 is relatively large as compared with the angle of deflection that will ordinarily have to be used, but in order to clearly bring out the placing of the different members this angle has been slightly exaggerated. However, it should be noted that the limited angle at which the deflected hole may be bored to the original hole depends primarily upon the flexibility of the small drill rod 25, and that a greater angle of deflection may be obtained by using any one of a number of known flexible power transmitting devices.

The deflecting face 5 need not necessarily be concaved, it being possible to deflect a hole by leaving this face 5 flat. This flattened face will guide the cutting mechanism sufficiently accurately where the original hole is not of great depth and the deflected hole is not of great length. However, the concave guide face 5 is preferably used since it guides the cutting mechanism more accurately, and since it facilitates the use of a cutting mechanism of the same size as was used in boring the original hole, although, as is apparent, this apparatus will guide accurately a smaller cutting mechanism. This latter feature is very important, especially in the core drilling operations, since it permits the removal of a core of the same size as was removed from the original hole.

When the deflected hole has been completed and it is desired to remove the deflecting means, this may be readily accomplished by using a hook suitably attached to the lower end of the drill rod 7. This hook is projected into the hole and is worked back and forth until it catches in the hole 8 of the wedge element 2. If hydraulic pressure or other force be applied to raise the rod 7 vertically, this pressure will be transmitted through the wedge elements and pipe section 11 to the plug 16 and shear the lower spikes 18, thus separating the main portion of the deflector from the smaller and less costly anchorage means. It is not essential to the operation of the present device that the interlocking means 13 and 14 carried by the pipe sections 11 and 12, respectively, be used, but where the shearing action may be difficult the cooperating surfaces of the interlocking teeth tend to rotate the pipe section 11 slightly on the pipe section 12 and increase materially the shearing action.

If it is desired to save the whole deflector, as may be necessary in core drilling in remote places where it is difficult to obtain spare parts, water may be poured into the hole to loosen the material which binds the

anchor 12 to the wall of the hole. For assisting this operation, the hole 9 has been formed in the lower wedge section to permit water to flow into pipes 11 and 12, a small hole being preferably formed in the plug 16 to permit water to flow into the center of the lower pipe.

It should be noted that my improved hole deflecting means may be constructed to deflect a hole at any angle and used to bring this about in any direction desired from the original hole, and it should be further noted that any number of deflections may be made from the original hole at about the same point therin by changing the position of the deflector in the hole. If it is desirable to deflect a hole at any point above or below the original deflection, longer or shorter anchorage pipes may be used or the hole may be filled in for some distance to provide a base on which the deflecting means may rest.

It should further be noted that my hole deflecting means is composed of but a few strong, easily assembled parts capable of withstanding the hard usage to which they are subjected. Another improved feature of this device is that the drilling mechanism is easily formed from the original drilling mechanism by merely adding the small drill rod 25 with the proper coupling means, and the swelled reaming coupling 22, if it is necessary to use the latter.

While I have in this application specifically described one embodiment which my invention may assume in practice, it is to be understood that the same is used for illustrative purposes only and that the invention may be modified to assume various forms without departing from its spirit or the scope of the appended claims.

What I claim as new and desire to secure by Letters Patent is:

1. In a hole drilling apparatus, a raising and lowering member, a deflector having a long inclined deflecting face formed thereon, and means for securing said member to said deflector, said securing means being releasable by a predetermined force applied to said member.

2. In a hole drilling apparatus, a supporting member, a deflector interlocking with said member, and means for securing said member and deflector, said securing means being releasable by a predetermined force applied to said deflector.

3. In a hole drilling apparatus, a deflecting member, a supporting member therefor, and means comprising an element more rigidly secured to one of said members than to the other for uniting said members.

4. In a hole deflecting apparatus, a supporting member insertable into a hole, means for securing said member in the hole, a deflecting device, and means comprising an

element more rigidly secured to said device than to said member for uniting said device and member.

5. In a hole deflecting apparatus, a supporting member insertable into a hole, means for securing said member in the hole, a deflecting device, an interlocking means between said member and device comprising mating teeth having inclined surfaces formed on said member and device, and means comprising an element more rigidly secured to said device than to said member for uniting said device and member.

6. In a hole drilling apparatus, a supporting member insertable into a hole, means for securing said member in the hole, a deflecting device, interlocking means between said member and device comprising interlocking projections on said members having parallel contacting faces arranged at an angle to an element of the surface of said member, and means arranged between said device and said member and secured to each of them for uniting them.

7. In a core drilling apparatus, a flexible cutting mechanism having a plurality of cutting tools mounted in longitudinal spaced relation thereon, and a deflecting mechanism cooperating therewith to change the direction of the hole.

8. In a core drilling apparatus, cutting mechanism comprising a relatively inflexible drill rod, a relatively flexible rod secured to the lower end thereof, a cutting tool mounted on the flexible rod, and a deflecting mechanism cooperating to change the direction of the hole, whether the same be vertical or inclined.

9. In a core drilling apparatus, a cutting mechanism comprising a relatively inflexible drill rod, a flexible drill rod attached thereto and a drill member having longitudinally spaced cutting and reaming elements, and a deflecting device adapted to deflect the axis of said drill member from alinement with that of the first mentioned drill rod.

10. In a deflecting apparatus for use in deflecting the hole drilled by a core drill, a deflector having a guiding means, anchorage means for said deflector, and a cutting mechanism cooperating therewith for making a deflected cut, said cutting mechanism comprising a plurality of longitudinally spaced cutting tools and a flexible means for operating the tools.

11. In a deflecting apparatus for use in deflecting the hole drilled by a core drill, a deflector having a guiding surface, detachable anchorage means for said deflector, and a cutting mechanism cooperating with said deflector for making a deflected cut, said cutting mechanism comprising a cutting tool, a reaming tool, and a flexible means for operating the tools.

12. In a core drilling apparatus, drilling

means, a relatively inflexible drill rod, and means for drilling a deflected hole at an angle greater than the maximum possible angle between the axes of the rod and of the hole, said means comprising a deflecting device and a connection between said rod and drill whereby the latter may be laterally deflected relative to the former and being operative to effect the drilling of holes inclined to the vertical.

13. In a core drilling apparatus, drilling means, a relatively inflexible drill rod and means for drilling a deflected hole at a depth

such that the angle of deflection will be greater than the possible angle between the 15 rod and the axis of the original hole, said means comprising a flexible connection to be inserted between the first mentioned rod and the drilling means, and a deflecting means having a surface making an angle with the 20 axis of the hole substantially equal to the desired angle of deflection said means being operative to effect the drilling of holes inclined to the vertical.

In testimony whereof I affix my signature.

JOSEPH STUART MITCHELL.
